US00D765122S

(12) **United States Design Patent**
Walters et al.

(10) **Patent No.:** **US D765,122 S**
(45) **Date of Patent:** **** Aug. 30, 2016**

(54) **DISPLAY SCREEN OR PORTION THEREOF WITH GRAPHICAL USER INTERFACE FOR CREATING AND ADMINISTERING A USER GROUP FOR A VIDEO COMMUNICATION DEVICE**

(71) Applicant: **Sorenson Communications, Inc.**, Salt Lake City, UT (US)

(72) Inventors: **Lane Walters**, American Fork, UT (US); **Merle L. Walker**, Sandy, UT (US); **Tara Ault**, Salt Lake City, UT (US); **Jarret M. Gill**, Sandy, UT (US)

(73) Assignee: **SORENSEN COMMUNICATIONS, INC.**, Salt Lake City, UT (US)

(**) Term: **15 Years**

(21) Appl. No.: **29/539,678**

(22) Filed: **Sep. 16, 2015**

Related U.S. Application Data

(63) Continuation of application No. 13/840,659, filed on Mar. 15, 2013, now Pat. No. 9,325,753.

(57) **CLAIM**

The ornamental design for a display screen or portion thereof with graphical user interface for creating and administering a user group for a video communication device, as substantially as shown and described.

DESCRIPTION

FIG. 1 is a front view of a display screen or portion thereof with graphical user interface for creating and administering a user group for a video communication device, showing a first embodiment thereof;

FIG. 2 is a front view of a second embodiment thereof;

FIG. 3 is a front view of a third embodiment thereof; and,

FIG. 4 is a front view of a fourth embodiment thereof.

The broken line showing of the display screen and graphical user interface are included for the purpose of illustrating environmental structure and portions of the article and form no part of the claimed design.

1 Claim, 4 Drawing Sheets

User Group: Add Communication Devices

List one or more communication devices you desire to add to the user group:

Group Unique Identifier: 1234

Then click "Next."

Next Back Cancel

User Group Settings: View Invitation Status

Select one or more communication devices you desire to remove from the user group:

Communication Device 1 Accepted

Communication Device 2 Rejected

1234

Then click "Next."

Next Back Cancel
